Primary Examiner — Susan E Krakower*Assistant Examiner* — Lisa A Grabenstetter(74) *Attorney, Agent, or Firm* — Robert J. Lauson;
Lauson & Tarver LLP(57) **CLAIM**

I claim the ornamental design for a purse, as shown and described.

DESCRIPTION

FIG. 1 is a perspective view of a purse, showing my new design.

FIG. 2 is a front elevation view thereof.

FIG. 3 is a rear elevation view thereof.

FIG. 4 is a right side elevation view thereof, the left side elevation view being a mirror image thereof.

FIG. 5 is a top plan view thereof; and,

FIG. 6 is a bottom plan view thereof.

The broken lines represent unclaimed portions of the design.
